UNITED STATES PATENT OFFICE.

NICHOLAS BRAYER, OF ROCHESTER, NEW YORK.

DESIGN FOR MONUMENTAL URN.

Specification forming part of Design No. 6,785, dated July 29, 1873; application filed June 25, 1873.

To all whom it may concern:

Be it known that I, NICHOLAS BRAYER, of the city of Rochester, county of Monroe and State of New York, have invented a Design for a Monumental Urn or Vase, of which the following is a specification:

The nature of my design is fully represented in the accompanying photographic illustration, to which reference is made.

The design is formed by a square pedestal, B, somewhat narrower at the top than at the base, and surmounted by a heavy ogee-molding upon which the vase A rests, the latter also forming part of the design. The panels of the pedestal are ornamented with Thorwaldsen's "morning" and "evening" in relief, as

shown. The basin of the vase A is ornamented with a row of cherubic faces in relief, as represented in the photograph. The vertical portion of the basin is ornamented with oak-branches, leaves, and acorns, in relief.

What I claim as my invention is—

1. The design for a vase, A, as shown and described.
2. The design for a monumental urn formed by the vase A and pedestal B, when ornamented as shown and described.

N. BRAYER.
